THERMIONIC DEVICE

Application filed February 12, 1925. Serial No. 8,722.

My invention relates to thermionic devices for the transmission and reception of radiant energy.

In the present thermionic devices of the audion type, as exemplified in the well known radiotrons of the W. D. & U. V. type, the leads from the plate, grid and filament extend from the interior of the tube for a considerable distance to the contact points on the base in close proximity and substantially parallel to each other. Audions having their leads arranged in this manner may be successfully used for the reception of broadcasting upon comparatively long wave lengths and low frequencies but are wholly unadapted for the reception of waves transmitted at very high frequencies and correspondingly short wave lengths. This is due to the inherent capacity in the tube itself, resulting partially from the arrangement of the tube elements themselves, and partially from the arrangement of the leads which extend from the tube elements to the contact points. What is termed the "capacity coupling" in the present type of tube is further increased by the arrangement of the contact "springs" in the present type of socket which comprise comparatively large areas of metal in close proximity.

I find that while the present type of tube is not adapted, nor can it be used in its present form for the reception of signals transmitted upon an extremely short wave length, very successful results are attained by removing the base of any of the present tubes and separating the leads as widely as possible. While the removal of the base and the divergence of the leads produces satisfactory results, such a tube is difficult to mount and connect in a radio receiving apparatus. My invention therefore contemplates not only a new form of base for a thermionic device, in which the leads may be separated as widely as possible and in which they are arranged in a non-parallel relation, but also a socket adapted to receive my new form of base and in which conductors will continue to diverge.

It is well known that in the present form of tube, the prong leads extending through the base of the tube do not make a very satisfac-

tory contact with the leads extending from the socket. Therefore, another object of my invention is to provide a combined tube and socket in which the electrical contacts will be very positive, will be made with a wiping motion which will tend to keep the surface of the contacts always clean, and in which contacts through solder will be eliminated.

With these objects in view my invention resides in the new form of base for a thermionic device in which the leads from the tube are widely separated and disposed in non-parallel directions, and in the new form of socket having widely separated and diverging leads, and in the novel manner in which the electrical connection is made between the leads from the tube elements and the leads in the socket.

In the drawing—

Fig. 1 is a vertical meridian section of one species of my tube and base;

Fig. 2 is an outside elevation of the same species of my tube and base;

Fig. 3 is an enlarged fragmentary section of the base of this species illustrating the manner in which the leads are connected to the contact points;

Fig. 4 is a plan view of a socket for this species;

Fig. 5 is a front elevation of the socket in which a portion thereof is broken away for the purpose of illustrating the interior construction thereof;

Fig. 6 is a fragmentary section of this base and socket showing the manner in which they co-operate, with the base partially inserted in the socket;

Fig. 7 is similar to Fig. 6 and illustrates the manner in which the spring contact in the socket is deflected when the base is pushed down into the socket;

Fig. 8 is a vertical meridian section of the preferred form of my tube and base;

Fig. 9 is an outside elevation of the preferred form;

Fig. 10 is a plan view of my preferred form of socket;

Fig. 11 is a front elevation of my preferred form of socket in which a portion thereof

is broken away for the purpose of illustrating the interior construction thereof.

Fig. 12 is a fragmentary section of a preferred form of envelope for my tube which extends only a short distance below the glass press which seals the leads.

In the drawing, 1, represents the glass envelope inclosing the tube elements. 2, represents the "press" through which extends the plate lead, 3, the grid lead, 4, and the filament leads 5 and 6. 7, represents the cup-like base into which the glass envelope, 1, is inserted and secured by means of cement, 8. This base is preferably of bakelite but may be made of any suitable material having a like high dielectric resistance. The base, 7, about its circumference, is provided with four recesses 9, 90 degrees apart. Inserted in these recesses are the thin metal contact cups or linings, 10, to which are soldered the four leads from the tube elements. The metal linings, 10, are formed of brass strips bent as shown in Fig. 3, to provide a small recess in the center thereof and having a small hole therethrough in the center of the bottom of the recess through which the respective leads are inserted and secured by means of a drop of solder 11 (see Fig. 3). Referring to Fig. 3, it will be noted that the ends of the linings, 10, do not extend to the exterior surface of the base but that a small portion, 12, of the insulating material is left to provide a means of retaining the lining in place. The linings, 10, may, if desired, be molded in place, or, the recesses, 9, may be molded in the base and linings, 10 "snapped" into place after the base is completed. Immediately below each of the recesses, 9, and extending to the bottom of the base, 7, is a recess, 13, having its inner face, 14, inclined as shown for a purpose which will be apparent as the description proceeds.

Referring to Figs. 4 and 5, my socket comprises an integral unit of bakelite or other material having a like high dielectric strength. The socket is provided with a base, 15, and a hollow cylindrical portion, 16, adapted to receive the base, 7, of the tube. The cylindrical portion, 16, in the form of base shown in Fig. 4, is provided with four recesses, 17, ninety degrees apart, from which project the resilient contacts, 18. These contacts are preferably of bronze or other resilient material of good conductivity, and bent to the configuration shown which is such that they recede from the cylindrical portion, 16, in diverging directions. The contacts, 18, extend from the interior of the cylindrical portion, 16, to the exterior, through the openings 19. One of these openings is shown in section in Fig. 5. The contacts, 18, are secured to the base, 15, by means of the screws, 20, and nuts, 21 (see Fig. 5). The nuts, 21, are countersunk into the base, 15, so that the tops thereof are substantially

flush with the top of the base, 15. The portions of the screws, 20, which extend above the nuts, 21, receive the knurled nuts, 22, to form binding post for connections. The contacts, 18, may extend beyond the base, 15, as shown, and may have their ends, 23, bent into cylindrical shape for the purpose of making soldered connections here if desired.

When the tube is inserted in the socket as shown in Fig. 6, the spring contacts, 18, enter the recesses, 13, on the base of the tube as shown. It will be noted from an examination of Fig. 6, that the back, 14, of the recess, 13, is substantially tangential to the curve of the spring contact, 18. Referring to Fig. 5 it will be noted that there is a slight space, 24, between the bottom of the recess, 17, and the contact, 18, when the contact is in its normal unstressed condition. Referring to Fig. 6 it will be noted that as the base, 17, is inserted in the socket the contact, 18, is forced down against the bottom of the recess, 17. As the tube is pushed down solidly in the socket as shown in Fig. 7, the contact, 18, is deflected upwardly and outwardly, so that finally, when the tube is pushed completely into the socket, the contacts, 18, will "snap" into the metal lined recesses, 10, of the base, 7, thus providing a positive and efficient electrical contact. Bearing in mind that one of the important features of my device is to provide a tube and socket having a very small inherent capacity, the contacts, 18, are so shaped that they are disposed in diverging non-parallel relation to each other.

The preferred forms of my tube and socket are shown in Figs. 8, 9, 10, 11 and 12. In my preferred form of base the leads from the tube elements diverge as soon as possible after leaving the glass press, 2, and are carried around the lower edge of the glass envelope in the same manner as shown in Fig. 1. In this preferred form of base instead of providing recesses therein as shown in Fig. 1, I provide projections, 25, of substantially the same construction as now used in the art but which in present practice extend through the bottom of the base instead of the side. These radial projecting pins are merely hollow tubes of brass or similar material provided with collars, 26, which are countersunk in the exterior of the base, and are secured in the base by upsetting the inner ends as shown at 27. The leads from the tube elements are pulled through the tubes, 25, and secured therein by a small drop of solder, 28, at the exterior end.

The cylindrical portion, 16, of the socket shown in Fig. 10 is provided with radial recesses, 28, ninety degrees apart, and adapted to receive the projecting contacts, 25, of the base, 7. The lower parts of the recesses 28, are laterally enlarged as shown at 29, in Fig. 11, for the purpose of receiving the clip, 30, on the contacts, 31. The contacts, 31, are

preferably of bronze or other resilient material and comprise a flat portion, 32, extending from the interior to the exterior of the socket and have the clip, 30, formed on the interior end thereof. The normal internal diameter of the clip, 30, is somewhat less than the diameter of the pins, 25, so that when the tube is inserted in the socket the pins, 25, may be "snapped" into the clips, 30, to form a positive and efficient electrical contact. The contacts, 31, like the contacts, 18, are recessed into the base, 15, and secured thereto by screws, 20, and nuts, 21. The upwardly projecting portion of the screws, 20, receive the knurled nuts, 22, to form binding posts. The exterior ends of the contacts, 31, may be extended beyond the base, 15, if desired, and bent into cylindrical shape for the purpose of making a soldered connection here.

In order to insure that the tube cannot be inserted into the socket except in the correct position, I provide the usual pin, 33, projecting from the base of the tube and adapted to be received in the recess, 34, in the socket.

Figs. 1 and 8 illustrate the application of my invention to the present form of tube in which the portion of the glass, 35, is carried for a considerable distance below the "press", 2, before it is bent upwardly to form the envelope proper. This results in confining the leads in close proximity to each other for a greater distance than is necessary, thereby increasing the "capacity coupling" of the tube. In my preferred form, illustrated in Fig. 12, the bottom, 36, of the envelope does not extend any appreciable distance below the "press", 2, so that the leads may be splayed immediately after leaving the press and thus effect a considerable reduction in capacity.

While I have illustrated several ways in which the broad features of my invention may be embodied in a commercially practicable device, it is obvious that the wide separation and continued divergence of the leads may be effected by other constructions differing somewhat in detail from those here shown, but which are nevertheless within the scope of my invention as defined by the appended claim.

It is to be understood also, that the terms which I have used in describing my invention are terms of description and not limitation, and that while I have illustrated and described a tube having only four widely separated element leads, it is obvious that my invention is particularly adapted for use in connection with thermionic devices having a greater number of elements and a correspondingly greater number of leads extending therefrom.

What I claim is—

A thermionic device comprising an envelope containing a plate and grid and having a reentrant portion therein, a base on said en-

velope surrounding the reentrant portion and having electrical terminals on the sides thereof, and electrical conductors extending from said plate and grid, respectively, through the reentrant portion to said terminals and having no portions of substantial length, exterior of the reentrant portion, disposed in directions closely approaching a parallel, capacity-creating relation, whereby said device is adapted to function at high frequencies.
